UNITED STATES PATENT OFFICE.

LOUIS CHARLES REESE, OF SAGINAW, MICHIGAN, ASSIGNOR TO WERNER & PFLEIDERER CO., INC., OF SAGINAW, MICHIGAN, A FIRM.

OVEN-FURNACE.

1,253,188.

Specification of Letters Patent.

Patented Jan. 8, 1918.

Original application filed April 24, 1915, Serial No. 23,706. Divided and this application filed December 6, 1915. Serial No. 65,367.

To all whom it may concern:

Be it known that I, LOUIS CHARLES REESE, a resident of Saginaw, in the county of Saginaw and State of Michigan, have invented new and useful Improvements in 5 Oven-Furnaces, of which the following is a specification.

This invention relates to improvements in the furnace and heating arrangements of 10 ovens requiring higher temperatures, such as baking ovens, japanning and enameling stoves, drying kilns, annealing furnaces and the like, and has for its objects greater economy in fuel and labor and greater efficiency in producing and regulating the heat 15 required and in working such ovens than was possible to attain hitherto.

To this end, I employ a new inverted combustion furnace in which the fuel is burnt 20 by means of air preheated by the waste heat of the oven which may consist of the heat carried away to the chimney by the used fire gases, or of the heat absorbed by the outer 25 structure of the oven and lost to the surroundings. I also introduce air thus preheated into the fire chamber of the oven either in order to burn the combustible gases still contained in the fire gases leaving the 30 furnace, or in order gradually to cool the oven after the furnace has been put out of activity.

The novel features, arrangements, parts and combinations thereof which constitute this invention, are fully explained in the 35 following description of an example of its application which is also represented in the accompanying drawing forming a part of this specification. The drawing represents a vertical longitudinal section of a drying 40 oven or stove heated by the furnace and heating arrangements forming the object of this invention.

Like characters of reference indicate corresponding parts serving the same or a 45 similar purpose.

A is the oven and B the drying chamber thereof. B is heated by the fire gases passing through the channels C, C₁ and C₂ on their way to the chimney. Channels and 50 ducts of this kind surround the drying chamber B from all sides with the exception of the back which is heated directly by the back of the furnace. D is the fire chamber in which the fire gases coming from the in-

verted combustion furnace E are completely 55 burnt and give off their first and fiercest heat. F is a wide tube leading air for the combustion to the furnace E, the air being preheated during its passage through F by the used fire gases. G is a boxlike chamber 60 consisting of two compartments in which auxiliary air for the combustion in the furnace E is preheated by the hot brickwork underneath the fire chamber D. H is the channel leading the fresh fire gases from 65 E into D. I is the tube conveying air into the fire chamber D; this air is preheated by the hot brickwork forming the bottom of the chamber D and of its prolongation, the channel C.

The oven A is made of brick, and its back 70 surrounds the furnace E with exception of that part of its top containing the charging door and of the front which is covered with a suitable insulating material to prevent loss 75 of heat.

a is the top brickwork of A containing the flue a₁ leading the used fire gases from the broad heating channel C₂ to the chimney a₂. The latter is provided with the 80 damper a₃ for adjusting its draft according to the requirements of the furnace and the heating system.

In the example represented by the drawing, the draft of the chimney is shown as 85 the only means for sucking air through F and G into the furnace E for the combustion of the fuel therein and through I into the fire chamber D for admixture with the fire gases or in order to cool the oven and 90 for drawing the fire gases from E through the channel H, the fire chamber D, the heating channels C, C₁ and C₂ and the flue a₁ into the chimney a₂. Where the draft of the chimney is too weak for performing the 95 work required, or where the use of a proper chimney stack is impracticable, suitable fans may be used instead with advantage. A suction fan provided with proper means for regulating its effect may be arranged at the 100 top of the flue a₁, or the air inlets of the ducts F, G and I may be connected with tubes through which a fan drives the required quantities of air into the system.

a₄ is the partition wall between the flue 105 a₁ and the channel C₂, and a₅ is the ceiling of the drying chamber B and forms at the same time the bottom of C₂. The front wall

- a_6 incloses the door opening of B and contains at each side of same the heating channels C_1 connecting the top and bottom channels C and C_2 . a_7 is the floor of B and 5 contains at the same time the heating channel C and the fire chamber D. The foundation a_8 incloses the air tube I and the air heating chamber G. a_9 is the partition wall at the back of B between the latter and the 10 furnace E, and a_{10} the back wall of the oven A surrounding E as described. The drying chamber B is charged and emptied through the opening b provided with the outer door b_1 and the inner door b_2 .
- 15 The walls of the inverted combustion furnace E consist of the cast iron casing e, the cast iron top e_1 and the firebrick lining e_2 . The bottom of E is formed by the grate e_3 which is preferably a so-called rocking grate 20 and self cleaning. The top e_1 carries the door e_4 for charging the furnace with fuel. This door and all the other doors arranged at E and the ashpit belonging to E, must be constructed in such a manner and provided 25 with such appliances that they can be hermetically closed. In regard to the door e_4 , this is attained by the movable yoke e_5 straddling e_4 , and the screw e_6 passing through e_5 for tightening same. e_7 is a small door 30 arranged immediately above the grate e_3 for stoking the fire in case the grate should refuse to work; e_8 is the movable yoke and screw belonging to this door for tightening it. e_9 is the channel arranged at the top e_1 35 for conducting the preheated air from F around e_1 , then the through the narrower, but broad channel e_{10} arranged down along the front of the casing e between the channel e_9 and the inlet e_{11} into the burning fuel 40 above the grate. e_{12} is the ashpit belonging to E, but formed by a cast iron structure separate therefrom. e_{13} is the ashpit door which is provided with the tightening arrangement (yoke and screw) e_{14} . e_{15} is a 45 water pipe provided with the regulating cock e_{16} for letting water into the incandescent fuel in the furnace if so desired. e_{17} is the insulating material covering the front of the furnace E.
- 50 The tube F leading the air required for the combustion from the room in front of the oven A into the furnace E is arranged within the flue a_1 so that the hot, used fire gases passing therethrough to the chimney 55 a_2 preheat the air flowing through F to E. F is provided with the slide valve f for regulating the quantity of air entering into F according to the requirements, with the bend f_1 and the throttle valve f_2 worked by means 60 of the rod f_3 and the handle f_4 from the back of the oven.
- The air heating chamber G is composed of the compartments g_1 and g_2 communicating with each other. The front of the chamber G forms part of the back wall of the
- ashpit e_{12} . The air enters g_1 through the pipe g_3 provided with the slide valve g_4 for regulating the inflow of air, and passes then into the upper and hotter compartment g_2 which is subjected to the fierce heat in the 70 channel H and the fire chamber D, being separated therefrom only by a layer of fire bricks. The hot air leaving g_2 travels then upward through the pipe g_5 to the upper part of the furnace E which it enters at g_6 . 75 The flow of air through the pipe g_5 can be regulated by means of the throttle valve g_7 worked by the rod g_8 and the handle g_9 . The pipes g_3 and g_5 are arranged at the side of the furnace E in the brickwall a_{10} surrounding it.
- The fire gases produced in the furnace E enter into the channel H through a layer h of perforated bricks forming the lowest part of the back wall of E. The tube I 85 leading the preheated air into the fire chamber D is provided with the slide valve i for regulating the quantity of air entering it and ends in the perforated tube i_1 distributing the air across the whole width of the 90 fire chamber D.
- The *modus operandi* of the furnace E and of its accessories is as follows: Assuming the fire were to be started, the doors e_4 and e_7 of the furnace, the door e_{13} of the ashpit 95 e_{12} and the slide valve a_3 of the chimney a_2 are widely opened; straw, wood shavings, cottonwool or the like are then introduced into the furnace through the door e_4 and lighted. Dry wood is then added, and, as soon as the 100 latter burns well, a little fuel, coal, coke, peat or the like, to be used for the work. After this charge has burnt through and is beginning to become incandescent, the doors e_4 , e_7 and e_{13} are hermetically closed, and 105 the slide valves f and g_4 of the two air inlets of the furnace E are opened. After a short time the first small charge will be aglow and the furnace hot enough; it is then completely filled with fuel through the door e_4 , 110 and after the latter has been closed again, the heat produced is regulated by regulating the slide valves of the air inlets, f and g_4 . In this way the foreman, who works at the oven front, is enabled to regulate the heat 115 produced and thereby the temperature of the oven without leaving his place.
- If the fuel within the furnace is quite incandescent, producer gas may be made by limiting the quantity of air let into the furnace to the required amount, using mainly the air inlet g_5 . In this case a small amount of water may be introduced into the furnace through the water pipe e_{15} . Air is then introduced into the fire chamber D through 120 the tube I in quantities regulated according to requirements by means of the slide valve i. As soon as air and gas meet in the redhot chamber, the latter lights up immediately 125 without any danger of explosion.

Another object of the airpipe I is to introduce air into D, after the air inlets f and g₄ have been closed and thereby the combustion in the furnace E stopped, in order to 5 cool the fire chamber D and thereby the oven.

I claim:—

1. In an oven furnace, in combination, a fuel chamber having a grate for its bottom, sidewalls containing at their lower part somewhat above the grate an opening serving as outlet for the combustion gases and a small, hermetically closing door for stoking, and a top provided with a hermetically 10 closing door for charging fuel into the said fuel chamber and an opening serving as inlet for the air for the combustion thereof, a preheater connected to this inlet and so arranged that the air passing therethrough 15 into the said fuel chamber is preheated by the spent firegases, a channel running inside the said fuel chamber from said air inlet along said top and down one of said side walls and leading the said preheated air 20 into the burning fuel at a point opposite to the said outlet for the combustion gases, and a closed ash pit arranged underneath the said grate and provided with a hermetically 25 closing door for cleaning the same.

2. In an oven furnace, in combination, a fuel chamber having a grate for its bottom, sidewalls containing at their lower part somewhat above the grate an opening serving as outlet for the combustion gases and a small, hermetically closing door for stoking, and at their upper part an air inlet, and a top provided with a hermetically closing door for charging fuel into the said fuel 30 chamber and with an opening serving as inlet for the air for the combustion, a pre-heater connected to this inlet and so arranged that the air passing therethrough 35 into the said fuel chamber is preheated by

the spent fire gases, a channel running inside the said fuel chamber from said air inlet 45 along said top and down one of said side walls and leading the said preheated air into the burning fuel at a point opposite to the said outlet for the combustion gases, a second air preheater connected to the said air 50 inlet in the upper part of the sidewalls of the said fuel chamber, and a closed ashpit arranged underneath the said grate and provided with a hermetically closing door for 55 cleaning the same.

3. In an oven furnace, in combination, a fuel chamber having a grate for its bottom, sidewalls containing at their lower part somewhat above the grate an opening serving as outlet for the combustion gases and a small, hermetically closing door for stoking, and a top provided with a hermetically 60 closing door for charging fuel into the said fuel chamber and with an opening serving as inlet for the air for the combustion 65 thereof, a preheater connected to this inlet and so arranged that the air passing therethrough into the said fuel chamber is preheated by the spent fire gases, a channel running inside the said fuel chamber from 70 said air inlet along said top and down one of said side walls and leading the said preheated air into the burning fuel at a point opposite to the said outlet for the combustion gases, a water pipe arranged and provided with means for leading water in regulated quantities into the upper part of the 75 said fuel chamber, and a closed ashpit arranged underneath the said grate and provided with a hermetically closing door for 80 cleaning the same.
